UNITED STATES PATENT OFFICE.

ARTHUR V. CONOVER, OF NEW YORK, N. Y., ASSIGNOR TO INTERFLASH SIGNAL CORPORATION, OF NEW YORK, N. Y., A CORPORATION OF NEW YORK.

GAS JET AND MEANS FOR IGNITING SAME.

Application filed May 11, 1926. Serial No. 108,239.

The present invention relates to gas burners, more particularly of the acetylene type now commonly used in beacon lights, and has for an object, the provision of a more 5 adequate igniting mechanism.

In the V-type burner commonly used, jets of gas flow from each arm of the V, impinging against each other at a point directly above the stem of the burner and 10 causing a spread of gas to give a broad flame as a light source. Heretofore, a pilot light has been supplied which ignites one of the jets and causes the flame to travel up to their intersection and down the other jet 15 to fully ignite the same. In the time interval required for the full ignition to take place, a quantity of gas has escaped which is not completely burned and the explosion which results from igniting the escaped gas 20 causes the incomplete products of combustion to be precipitated upon the surrounding lens and globe with the result that the same must be frequently cleaned. Where rapid and intermittent flashing takes place, 25 the repeated explosions cause this to be a decided disadvantage.

The apertures of the pilot lights are usually quite small and frequently become clogged. Where the light operates for long 30 periods of time without human supervision, the results of such clogging would be disastrous and it becomes an important consideration to insure absolutely reliable service. By providing a pilot light for each jet the 35 factor of safety in operation is increased 100%.

The present invention overcomes the above disadvantage by providing a pilot light for each jet and thus causing the same 40 to be ignited at its source. It will be seen that there will be no escaping gas and hence no explosion and the objectionable blackening of the lens and globe is reduced to an absolute minimum.

Reference will now be had to the accompanying drawings forming a part hereof wherein:

Figure 1 is a top view, partly in section, of a preferred form of the invention.

Figure 2 is a side elevation, partly in section, of the burner shown in Figure 1.

Figure 3 is a section taken on the line 3—3 of Figure 2.

In the drawings, *a* represents a fixture 55 formed at its lower extremity with a thread-

ed socket *a'* which engages a supporting standard *a²*. Threaded recess *a³* at the top and center of the fitting receives a mounting socket *b* which secures the V burner *c* with its arms *c'*.

On the rear face of the fitting *a* another recess *a⁴* is provided which communicates with the gas reservoir and a passage *a⁵* conducts the gas from this recess, through the fitting *a*, passage *b'* in mounting *b* and branch passages *c²* in the arms *c'* of the burner *c* to the respective orifices *c³*. A proper mixture of air and gas is obtained in the wells *c⁴* through the apertures *c⁵*.

On the front face of the fixture *a*, a third recess *a⁶* is provided which communicates with a suitable source of supply for the pilot lights. Divided passages *a⁷* lead to either side of the fitting and communicate with chambers *a⁸* which, in turn, communicate, 70 through passages *a⁹*, with tubes *d*. These tubes extend upwardly and across the burner and are joined in the valley of the V burner. Obviously this may be a single U-shaped tube with its ends extending into fixture *a*. 80

A partition *d'* separates the gas in one side of the fixture from that in the other. Secured to the tube at the partition are burners *d³* which are parallel to their respective burner arms *c'* and which communicate with the tube *d* on either side of the partition by apertures *d²*. It will be seen that the burners *d³* will direct pilot lights into the jets from the burners *c'*, which lights are supplied from independent parts 85 of the tube *d*.

The flow of gas to the independent portions of the tube is regulated by means of needle valves which are constructed as follows. Communicating with chambers *a⁸* are threaded nipples *a¹⁰* in which are screwed taps *e*. The outer ends of taps *e* have outwardly projecting threaded studs *e'* which have hollowed portions *e²*. Through the center of the taps *e* are screwed stud bolts *f* which have needle valve heads *f'* adapted to co-operate with the ends of the passages *a⁷* to restrict the flow of gas through the chambers *a⁸*. Between the heads *f²* of the bolts *f* and the taps *e* and seated in the hollowed portions *e²* are springs *g* which serve to more effectively and positively secure the bolts in adjusted positions. 100

Internally threaded caps *h* screw over the studs *e'* and serve as a protection for the 110

valve heads f^2 . The ends of the caps may be provided with socket wrenches h' which fit the valve heads and thus serve as a convenient adjusting means.

5 Secured to the vertical portions of tubes d , as by crimping or soldering, are cooling vanes i . These vanes dissipate the heat in the tubes resulting from their proximity to the flames, which heat has been found to oftentimes cause the gas therein to be ignited before leaving the apertures d^2 .

Manifestly, the structure could be modified so that both pilot lights would be fed from a single tube d , in which cases there 15 would be only one needle valve and the partition d' would then be removed. In such case, of course, the aperture for each jet, being of the usual size, will be subject to clogging. In this respect provision of separate pilot lights would be equally as advantageous as in the former case. Other changes could be made and features modified to conform to the needs of particular installations and the invention is not to be limited 25 except as defined by the appended claims.

What I claim is:

1. In a burner supplying gas for combustion in a single flame, a plurality of jets and a plurality of pilot lights to ignite the 30 jets.

2. In a burner supplying gas for combustion in a single flame, a plurality of jets, means for causing the jets to impinge against each other, and a plurality of pilot 35 lights to ignite the jets.

3. In a burner for supplying gas for combustion in a single flame, a burner fixture, burners carried by the fixture, means for supplying gas to the burners through the fixture, a plurality of pilot light burners carried by the fixture, and means for supplying gas to the lights through said fixture.

4. In a burner for supplying gas for combustion in a single flame, a burner fixture, burners carried by the fixture and formed to produce a single flame, means for supplying gas to the burners through the fixture, a plurality of independent pilot light burners carried by the fixture, and independent means for supplying gas to each of said lights.

5. In a burner for supplying gas for combustion in a single flame, a burner fixture, burners carried by the fixture and formed to produce a single flame, means for supplying

gas to the burners through the fixture, a plurality of independent pilot light burners carried by the fixture, and independent means for supplying gas through the fixture to each of said lights. 55

6. In a burner for supplying gas for combustion in a single flame, a burner fixture, burners carried by the fixture and formed to produce a single flame, means for supplying gas to the burners through the fixture, a plurality of independent pilot light burners 60 carried by the fixture, independent means for supplying gas through the fixture to each of said lights, and independent means on said fixture to regulate the flow of gas to each of said lights. 65

7. In a burner for supplying gas for combustion, a fixture, V-shaped burners carried by the fixture, a passage in the fixture for supplying gas to the burners, a tube carried by the fixture and leaving a portion of its length lying within the burner, a partition in the tube at the burner, pilot light burners carried by the tube on either side of the partition, separate passages in the fixture communicating with either end of the tubes, 70 separate means to regulate the flow of gas in the passages, and means in the fixture to supply gas to the passages. 80

8. In a burner, a fixture, a burner carried by the fixture, means for supplying gas to the burner, a pilot light for igniting the gas from the burner, means for supplying gas to the pilot light, and means for cooling said last named means. 85

9. In a burner, a fixture, burners carried by the fixture, means for supplying gas to the burners, a pilot light for igniting the gas from the burners, a tube for supplying gas to the pilot light, and means on the tube for exerting a cooling effect on the same. 90

10. In a burner, a fixture, burners carried by the fixture, means for supplying gas to the burners, a pilot light for igniting the gas from the burners, a tube for supplying gas to the pilot light, and vanes on the tube for exerting a cooling effect on the same. 100

11. In a burner supplying gas for combustion in a single flame, a plurality of jets, and a pilot light for each jet to ignite the same. 105

This specification signed this 8th day of May, A. D. 1926.

ARTHUR V. CONOVER.
